UNITED STATES PATENT OFFICE

EDWIN E. SLICK, OF PITTSBURG, PENNSYLVANIA.

APPARATUS FOR ROLLING FLANGED SHAPES.

No. 887,534.

Specification of Letters Patent.

Patented May 12, 1908.

Application filed February 12, 1906. Serial No. 300,596.

To all whom it may concern:

Be it known that I, EDWIN E. SLICK, of Pittsburgh, Allegheny county, Pennsylvania, have invented a new and useful Apparatus for Rolling Flanged Shapes, of which the following is a full, clear, and exact description, reference being had to the accompanying drawings, forming part of this specification, in which—

10 Figures 1 and 2 show the rolls with the successive passes arranged in accordance with my invention in two three-high mills, and Fig. 3 is a view similar to Fig. 2 showing a different arrangement of the finishing passes.

15 My invention relates to apparatus for rolling shapes having wide flanges, and it is designed to produce such shapes without the use of universal mills.

In the drawing, Fig. 1 shows a three-high mill having rolls 2, 3 and 4, and containing five passes. I start with a bloom or billet, which in passing through the first pass *a* is provided with the longer diagonally opposite flanges 5 and 6 and with the shorter rudimentary flanges 7 and 8. The metal then returns through the pass *b*, in which the flanges 7 and 8 are widened and the flanges 5 and 6 are contained in the dead groove, and hence not widened. It will be noted that the flanges 5 and 6 which are in the live groove in the first pass are in the dead groove in the second pass. It will also be seen that the live grooves are formed by substantially flat faces which taper or converge toward each other outwardly, with an open space at the end of the pass. The live grooves therefore are always open, and the dead grooves always closed; and by making the faces of the live grooves substantially flat and outwardly converging, I obtain the very substantial widening of two of the flanges.

In the third pass *c* the flanges 5 and 6 are within the live grooves and are therefore widened while the flanges 7 and 8 are within the dead grooves and are not widened.

In the next pass *d* the flanges 7 and 8 are widened in the live open grooves, while the flanges 5 and 6 are within the closed dead grooves.

50 In the fifth pass *e* the flanges 5 and 6 are widened in the open live grooves, while the flanges 7 and 8 are within the dead grooves.

In the pass *f* of the second set of rolls 9, 10 and 11, the flanges 7 and 8 are widened and made thinner in the live grooves, while the flanges 5 and 8 are within the dead grooves.

In this the sixth pass, the flanged shape, which in this case is a wide flanged I-beam, is brought substantially to its final dimensions, but the flanges are inclined outwardly in opposite directions. The next pass or passes are merely bending passes which bend the flanges into parallel planes to form the I-beam. 60

In the seventh pass *g* the web 12 is substantially horizontal, and the upper flanges 65 6 and 7 are bent into proper position, while the lower flanges 5 and 8 remain bent outwardly.

In the final eighth pass *h*, the flange 12 is horizontal, and the lower flanges 5 and 8 are 70 bent into planes at right angles to the web, thereby finishing the beam. In this second set of rolls I have shown supplemental passes *g'* and *h'*, so that the metal may be passed through either *g* or *g'* in the seventh pass and 75 either *h* or *h'* in the eighth pass.

It will be noted that in the bending pass or passes the web is supported by the rolls at the same time that the flanges are being bent to form. This is an important feature of my 80 invention, since it prevents buckling of the web and insures a good product. It will also be noted that in all of the reducing passes the web is at an angle to the axes of the rolls, this angle being reversed in successive passes. 85

In the modified passes of Fig. 3 the sixth pass *f'* is the same as the pass *f* of Fig. 2, but in the first bending pass *g'* the web 12' is not horizontal, but is inclined, and none of the flanges are bent into final position in this 90 pass. All of the flanges are bent toward their final position, and then in the final pass *h'* the web 12' is horizontal and the flanges 5', 6', 7' and 8' are bent to final position. In this case, as in the first form, the web is supported by the rolls at the same time that the flanges are being bent into their final position. There is also no turning of the blank to a position at right angles to the previous pass. It will be noted that this is the case 100 with all the passes.

The advantages of my invention result from the obtaining of shapes having wide flanges by means of ordinary mills other than universal mills having horizontal and vertical rolls. 105

By arranging the diagonally opposite flanges where such are present, alternately in the dead and live grooves, and by shaping the live grooves in the manner above described, I can obtain much wider and thinner flanges than have heretofore been gotten by 110

the use of ordinary mills. The bending of the flanged shape in passes which support the web is also of importance, as this prevents distortion of the web and insures a good product. It also avoids the necessity for turning the blank to an angle at 90° to the previous pass.

It not being necessary to turn the blank during the rolling operation, the usual manipulators or other turning devices usually employed are rendered unnecessary, and the difficulties experienced in the operation of this apparatus is avoided.

Instead of passing any flange alternately through a live groove and then through a dead groove at each successive pass, the flange may be passed through two live grooves before entering a dead groove, or two dead grooves before entering a live groove. This might be done where the mill would not permit a heavy draft, or for other reasons, and I intend to cover such variation in my claims.

Variations may be made in the mill or mills employed, in the contour of the flanged shape being rolled, in the number and width of the flanges, &c., without departing from my invention.

I claim:—

1. Apparatus for rolling wide flanged shapes comprising rolls having successive separate passes in which the web portion is at successively opposite angles to the axes of the rolls and in which similarly located flange portions in the successive passes alternately form an open live groove to draw out the flange between tapering substantially flat opposing faces and form a dead groove and a bending pass in which the flange portions of the pass bend the flanges to final position; substantially as described.

2. Apparatus for rolling shapes having wide flanges comprising rolls having a series of separate passes in which the web portion is inclined alternately at opposite angles to the axes of the rolls and in which similarly located flange portions in the successive passes alternately form an open live groove to draw out the flange to any width to which the metal will flow and form a dead groove in the next pass; substantially as described.

3. Apparatus for rolling flanged shapes comprising rolls having successive passes in which the web portion is at an angle to the axes of the rolls and in which similarly located flange portions in the successive passes alternately form an open live groove with tapering opposing faces to draw out the flange therein and form a dead groove in the next pass, and a bending pass in which the flange portions of the pass bend the flanges to final position and finish the shape; substantially as described.

4. Apparatus for rolling flanged shapes of general I-beam form comprising rolls hav-

ing successive passes in which the web portion is at an angle to the axes of the rolls and the flange portions form diagonally opposite open live grooves with tapering opposing faces to draw out the flange therein and diagonally opposite dead grooves, similarly located flanged portions in the successive passes alternately forming live grooves and dead grooves, and a bending pass in which the flange portions bend the flanges to final position, the top surface of the web portions of the passes contacting with the same surface of the shape in all of the passes; substantially as described.

5. Apparatus for rolling flanged shapes comprising rolls having passes in which the flange portions roll the shape with its flanges out of normal angular position to the web and a succeeding pass or passes in which the flange portions bend the flanges to normal position while the web portion supports the web of the shape throughout the bending operation, at least one of the flange portions of the pass being a dead groove and the top surface of the web portions of the passes contacting with the same surface of the shape in all of the passes; substantially as described.

6. Apparatus for rolling a shape, having at least two flanges, comprising rolls having passes in which similarly located flange portions of the passes form an open live groove having tapering opposing faces to draw out the flange and then a dead groove in alternate passes, with the web portion of the passes at an angle to the roll axes and a pass having flange portions in which the flanges of the shape are bent to final position, with the top surface of the web portions of the passes contacting with the same surface of the shape in all of the passes; substantially as described.

7. Apparatus for rolling shapes having wide flanges comprising rolls having a series of separate passes in which the web portion of the pass is inclined alternately at opposite angles to the axes of the rolls and the diagonally opposite flange portions of the passes form diagonally opposite open live grooves in which the flange is drawn out to any width to which the metal will flow and diagonally opposite dead grooves, similarly located flange portions alternately forming live grooves and dead grooves in successive passes; substantially as described.

8. Apparatus for rolling I-beams comprising rolls having passes with their diagonally opposite flange portions formed to bend the flanges out of normal position with the web and having passes with the flange portions formed to roll and bend the flanges to normal position and with web portions formed to contact with and support the web of the beam in each pass, the top surface of the web portion of the passes contacting

with the same surface of the beam in all of the passes; substantially as described.

9. Apparatus for rolling flanged shapes comprising rolls having passes with their flange portions formed to bend the flanges out of proper position relative to the web of the shape, the web portions of the passes being on an angle to the horizontal and having at least one bending pass in which

10 the web portion is parallel with the axes of the rolls and the flange portions are arranged

to bend the flanges, the web portion of the passes contacting with and supporting the web in each of the passes; substantially as described.

15

In testimony whereof, I have hereunto set my hand.

EDWIN E. SLICK.
